BANG CUTTER GUIDE

Nathan L. Solomon, P.O. Box 550,
Englewood, N.J. 07231Continuation-in-part of design application Ser. No.
82,256, Oct. 20, 1964. This application May 25,
1966, Ser. No. 2,431

Term of patent 14 years

(Cl. D86—10)

FIG. 1

FIG. 2

FIG. 3

FIG. 4

FIGURE 1 is a front perspective view of a bang cutter guide showing my new design;

FIGURE 2 is a front elevational view thereof;

FIGURE 3 is a bottom plan view thereof, portions of the elastic being shown broken away for convenience of illustration; and

FIGURE 4 is a side elevational view thereof.

This is a continuation-in-part of Design application Ser. No. 82,256, filed Oct. 20, 1964, and now abandoned.

I claim:

The ornamental design for a bang cutter guide, substantially as shown and described.
